UNITED STATES PATENT OFFICE

162,766

HOLDER FOR LIPSTICKS OR THE LIKE

Victor C. Wray, Los Angeles, Calif., assignor to Ranilom, Inc., Los Angeles, Calif., a corporation of California

Application May 1, 1950, Serial No. 9,616

Term of patent 7 years

(Cl. D86—10)

To all whom it may concern:

Be it known that I, Victor C. Wray, a citizen of the United States of America, residing at Los Angeles, in the county of Los Angeles, State of California, have invented a new, original, and ornamental Design for a Holder for Lipsticks or the like, of which the following is a specification, reference being had to the accompanying drawing, forming a part hereof.

and

I claim:

The ornamental design for a holder for lipsticks or the like, as shown.

VICTOR C. WRAY.
